UNITED STATES PATENT OFFICE.

LOUIS P. DISS, OF ILION, NEW YORK.

TYPE-WRITER.

935,301.

Specification of Letters Patent. Patented Sept. 28, 1909.

Application filed September 20, 1907. Serial No. 383,759.

To all whom it may concern:

Be it known that I, Louis P. Diss, of Ilion, in the county of Herkimer and State of New York, have invented certain new and useful Improvements in Type-Writers; and I do hereby declare that the following is a full, clear, and exact description thereof, which will enable others skilled in the art to which it appertains to make and use the same, reference being had to the accompanying drawings, and to the characters of reference marked thereon, which form part of this specification.

The object of my present invention is to provide certain improvements in typewriters of one of the forms of so-called visible writers, wherein provision is made for the mounting of a sufficient number of type bars in the machine without crowding or placing them in such close juxtaposition as to interfere with their ready placing, adjustment and removal; and further to provide such a construction wherein provision is made for the type when at rest to become arranged in a single semi-circular series and provision is made for adjusting and alining with facility and to enable the returning after removal to the same position with certainty.

A further object is to provide an improved bearing for the type bars, whereby the type bar is mounted for free action adapted to deliver the type on a printing point with great accuracy, and where wear is compensated for by the form of the bearing in a way to retain these advantages.

Figure 1 shows a sectional view of a typewriter frame in connection with type bars, type bar hangers and type bar actuating mechanism arranged therein, according to my present invention. Fig. 2 is a longitudinal section of a typewriter frame showing certain type bar hangers arranged in position therein. Figs. 3, 4 and 5 are details showing the three forms of type bars employed in my present construction. Fig. 6 is an enlarged sectional detail showing a type bar hanger and the manner in which it is mounted in the machine frame. Fig. 7 is a detailed view mostly in section on an enlarged scale of the type bar bearing.

Referring to the reference letters and figures in a more particular description, 1 indicates a typewriter frame which has in the present instance a segmental type bar hanger beam or segment 2 secured at its upper outer

ends in the main frame of the machine. This segment 2 is relatively wide from front to rear of the machine and on its upper or inner face is provided with shoulders or offsets whereon three sets of type bar hangers *a*, *b* and *c* are respectively mounted in the manner hereinafter pointed out. The hangers *a*, *b* and *c* are substantially similar and consist of a pair of spaced arms 3, which receive between their projecting ends the pivotal end 60 of the type bar and at their bases are provided with and secured to a vertical cylindrical shank or post 4. The post 4 is received in a cylindrical hole in the segment 2, and the same is secured and adjusted as follows: 70 A set screw 5 is provided to engage against the lower or outer end of the post 4 to adjust the same longitudinally in the opening in the segment. This set screw 5 is preferably mounted in a separate piece or strip 6, which may be secured to the body of the segment 2 proper by a suitable number of screws 7. Rotary adjustment of the hanger 4 is controlled by an adjustable stop provided in screw 8, which is adapted to engage not against the 75 center but against one corner of the hanger. When adjusted the hanger may be bound or secured in its position in the segment 2 by the set screw 9 extending through the 80 body of the segment and bearing against the post 85 4. The type bars 10, which are of three forms and three lengths, as shown in Figs. 3, 4 and 5, to adapt the pivotal end to reach the several pivotal points in the three banks of hangers *a*, *b* and *c*, are respectively pivoted 90 or hung, as hereinafter particularly described, in the upper or inner ends of the hangers respectively. The swinging ends of the type bars 10 are adapted to normally rest on a semi-circular rest or cushion 11 in a single row or series when in their normal out-of-use position, and the type bars are of such length as to deliver the blow of the type on the printing point of the platen 12.

For operating the several type bars there 100 are provided in the rear part of the frame a set of bell crank levers 13 pivoted in fixed brackets provided on a curved or segmental frame bar 14 in the rear portion of the frame. One arm of the bell crank 13 is relatively 105 long and the other short, and the long arm, which projects upwardly, is connected by a connecting rod 15 with an eye adjacent to the pivotal end of the type bar. The bell crank 13 is connected to and adapted to be 110

actuated from the key lever 16 by a thrust rod, as 17, extending between the rear swinging end of the key lever and the bell crank 13 and coupled to each. In order to better distribute the leverage, the key levers, as 16, are of two or more forms and preferably respectively mounted on the two sets of pivots 18 and 19. The keys provided on the respective key levers are indicated by 20.

10 It is evident that by arranging the type bar hangers in several banks or series they can be made larger and wider, and provision made for much longer type bar bearing than if the hangers were arranged in a single 15 row. It is also obvious that by the arrangement illustrated, each hanger is much more accessible.

10 The type bar pivot 25 is provided with conical bearings 25^a of a much sharper and 20 more pointed form than heretofore or ordinarily employed, and which may be denominated "acute" and which bearings are received in similar shaped bearing openings in the hanger walls 3. The conical bearing of 25 the pivot 25 runs into the body of the pivot in such manner as to afford a square shoulder as between the base of the bearing and the body of the pivot. This shoulder is adapted to engage against the wall of the 30 hanger around the conical bearing opening and resist any tendency of the bearing from wedging tightly in the bearing which on account of its "acute" form is liable to occur. A slight enlargement or boss, as 26, may be 35 provided around this bearing opening to engage the square shoulder on the end of the pivot if preferred, as shown in Fig. 7, although this is not essential. The parts are so proportioned that the wear on the square 40 shoulder will keep pace substantially with the wear on the conical parts, and by heading up a rivet 27 extending between the walls 3 of the hanger or tightening the screw at the same point occasionally, wear may be 45 taken up from time to time. It is obvious that with an obtuse form of conical bearing a portion of the force applied to the type bar is lost, being directed to wedging the bearing walls apart, while an acute form of conical bearing is liable to wedge in its bearing,

but furnishes better resistance to the force applied to operate the type bar.

The form of bearing herein shown overcomes the defects of both the obtuse and acute forms of conical bearing.

It is obvious that modifications and changes in and from the construction herein described may be made without departing from the spirit of my invention.

What I claim as new and desire to secure by Letters Patent is:

1. The combination in a typewriter of a segment, cylindrical shank receiving openings therein arranged with their axes directed substantially toward the printing point, type bar hangers having cylindrical shanks adapted to be received in said openings, means for adjusting a shank longitudinally in said openings and for rigidly securing the same in the opening, substantially as set forth.

2. In a typewriting machine, the combination of a segment having cylindrical shank receiving openings therein arranged in plural series with their axes directed substantially toward the printing point, type bar hangers having cylindrical shanks adapted to be received in said openings, means for rotatively adjusting the shanks in said openings and means for rigidly securing the shanks in the bar when adjusted, substantially as set forth.

3. In a typewriting machine the combination of type bar hangers having cylindrical shanks arranged in plural series, the axes of the shanks arranged substantially radial from the printing point, type bars mounted in the hangers with their pivots at various distances from the printing point and being of such various lengths that the type will strike a common printing point and form a single series at their rest, substantially as set forth.

In witness whereof, I have affixed my signature, in presence of two witnesses, this 16th day of Sept., 1907.

LOUIS P. DISS.
